JAMES BROWN AND JOHN MUNRO GLASS, OF EDINBURGH, SCOTLAND; SAID BROWN
ASSIGNOR TO SAID GLASS

APPLIANCE FOR INDOOR GAMES OF GOLF

Application filed June 9, 1927, Serial No 197,743, and in Great Britain December 2, 1926.

Our invention relates to an appliance for indoor game of golf, which for the time being we prefer to designate "Q-golf" because players may use cues as well as clubs, whereby any green in any part of the country can be represented.

The invention consists of many parts, such as a portable table of any suitable size in one piece or made up of sections of wood or any other suitable material connected and locked or held together by bolts or other suitable locking devices. The base of the table may have a permanent covering of rough felt or other suitable material fixed thereto. A ledging or skirting is set round the edge of the table, and held in position by suitable bolts, thumb-screws or such like. The base of the table which constitutes the putting green is formed by the provision of suitable borings of appropriate circumference on the top or plain side of the table or leaves forming the table, and suitable preferably adjustable legs are provided on the underside of the table or leaves of which the table is made up. If the base of the table is of thin wood or papier-mâché or other suitable material a block of wood or such like bored in the center is fixed at back of each hole to provide the depth and bottom for the hole.

Suitable courses are also provided and are made of any suitable cloth or material, such as a rough kind of plush, preferably green in colour and fashioned to resemble grass as near as possible, the edges of which are held down by the skirting or ledging and bolts hereinbefore referred to.

In the body of the rough cloth there are putting green holes which correspond with the borings in the table, throughout the entire course suitably adjustable representations of small hillocks, bunkers and such like are provided. These also may be permanently attached to the rough cloth, some on either side, and appropriate plugs are provided for the plugging up of the putting green holes,

with the exception of the hole or holes in play for the time being.

The adjustable hillocks and obstructions may be attached to the top of the several hole caps or plugs which fill up and conceal the putting green holes, one or more of which will, of course, be removed when the hole or holes plugged is or are in play. When a hole has been played, the plug-hole cap (with or without a particular obstruction) will be replaced in the hole, and the plug-hole cap with any obstruction relating thereto removed from the next hole it is desired to play, and so on.

Clubs similar in shape to ordinary golf clubs, but somewhat smaller and shorter and with the stems practically on a level with the head of the club are used, while cues may also be provided similar to ordinary billiard cues, although slightly more slender.

The balls are about 1" in diameter and are marked similar to ordinary golf balls and are made of any suitable material. Appropriate tees may be used.

In order that our invention may be properly understood and readily carried into effect, we have hereunto appended one sheet of drawings, of which

Figure 1 is a plan of the appliance illustrating our invention.

Figure 2 is a side view of Figure 1.

Figure 3 is a cross section of Figure 1.

Figure 4 is an enlarged sectional view of part of the appliance showing ball.

Figure 5 shows a method of attaching the sections together.

Figure 6 is an end view of Figure 5.

Figures 7 and 8 are respectively side elevation and plan of one club.

Referring to the drawings, A are the sections of which the table or course is made up and, as shown, two sections are hinged together by the hinges B and these sections are connected together by suitable catches C. The base of the table is, in this case, made of

thin material so that the putting holes H are increased in depth by the addition of the hollowed blocks O glued or otherwise attached on the underside of the base, but, of course, as previously explained, when the base of the 5 table is of material of sufficient thickness to provide for the proper depth of putting holes, the addition of the blocks is quite unnecessary. The legs D of the table may be of any 10 suitable design and are so attached to the body of the table as to be readily detachable when desired. J is the layer of felt or such like which is suitably fixed to the base of the table.

15 The table is covered over with a layer of rough plush K or such like, preferably green to as far as possible have the appearance of a real course. The plush K is held in situ by the skirting or ledging E pressing hard on the 20 top of the edge of the plush K which may be strengthened round the edge by leather, tape, or other suitable material, the skirting or ledging being retained in position and securing a firm hold on the plush K by the bolts 25 F and thumb-screws G. Holes H are provided in the plush K to correspond with the 30 holes in the table. The loose plugs I are preferably of colour to suit the colour of the course, one being in each hole H with the exception of that for which the golfer is playing.

35 The obstacles L are of any formation and may be placed in any part of the green and may be fixtures or otherwise, as desired. 40 The ball M is of such a size as to readily slip into the hole H, and N is one of the clubs which, as will be observed, has the club head practically on the same level or angle as the shaft or stem, all the different clubs being similarly made.

45 In use the drive must be made from a point indicated from one of the four sides of the table or course and the player must have driven the ball against the ledge of the course 50 opposite the driving point before he or she can proceed to play the ball towards the hole for the time being played. After the drive has been made, the player may use any of the clubs for the continuance of the play and, 55 when the putting green has been reached, the player may cue the ball.

60 The above appliance, it will be obvious, would be most useful on board ship, in clubs, hotels, as well as in private houses, and can 65 be made of any size to suit circumstances, and can be used without legs, the course being laid on any flat surface of sufficient height, or course, from the ground.

Claims:

70 1. A table for indoor golf having a top comprising a plurality of pairs of sections the sections of each pair being hingedly connected together and each member of one pair of sections being detachably connected to a 75 member of the adjacent pair of sections, and

80 a skirting extending around the sides of the table top and detachably bolted at spaced points to each member of each pair of sections so that the top is effectually braced and strengthened by said skirting.

85 2. A table for indoor golf as claimed in claim 1, including a cover on the top and in which the skirting or ledging is provided on the inner side with a flange which overhangs and bears on the edge portion of said cover.

90 In witness whereof we affix our signatures.

95 JAMES BROWN.
JOHN MUNRO GLASS.
